UNITED STATES PATENT OFFICE.

JOHN C. WAHL, OF CHICAGO, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING MACHINE.

Application filed May 23, 1911. Serial No. 629,308.

My invention relates to calculating machines, and in the present form is shown as an attachment to a typewriter. In my machine the totalizer may be made to automatically add in one column, subtract in another column, and not calculate in another column, depending upon the preadjustment of certain cams. A typical illustration of the utility of this characteristic is found in bankers' accounts where in one column or portion of the sheet the date and name of an item will be spelled out, in another column deposits will be added, and in another column withdrawals subtracted. One of the objects 15 of my invention is to provide means whereby the automatic operation above indicated may be temporarily superseded and the machine be made to perform straight addition or subtraction according to the problem temporarily in hand. To illustrate, in a banking 20 house the automatic mechanism would be so set as to normally make the machine add in one column, subtract in another column and not calculate in another column; but occasions might frequently arise where it would 25 be necessary to add or subtract in all of the columns or otherwise depart from the standard form of account, and it is my purpose to provide manually operated mechanism 30 capable of rendering the automatic mechanism non operative and simultaneously cause the machine to produce the kind of calculation required. The means whereby this is accomplished for convenience will be termed 35 the "setting mechanism" or manual controlling means, and in my machine the setting mechanism may be operated without disturbing the arrangement of the controlling cams which form part of the automatic controlling means. In the form of machine here 40 shown the setting mechanism may be instantly operated and is under the control of a single manually operated setting lever.

Another object of my invention is to provide means for correcting any mistakes which may have been made by the operator. As my machine is capable of both addition and subtraction, if the operator has added the wrong number the mistake may be corrected by subtracting the number actually 50 added, thus bringing the figure wheels back to the condition in which they were before the mistake was made and vice versa. It is my purpose to provide correcting mechanism 55 so constructed that after a mistake has been

made, the operator may, by merely throwing a lever, cause the machine to perform the reverse operation irrespective of whether the mistake was made during addition or subtraction. According to my invention the machine may be instantly reversed by depressing the correcting lever, and this reversal will take place whether the machine is set for automatic or manual control. In fact, the operator, upon discovering that he 60 has made a mistake, need not take the trouble to inform himself as to whether the machine was adding or subtracting when the mistake was made nor whether it was under automatic or manual control.

I accomplish my objects by the mechanism illustrated in the accompanying drawings, in which:

Figure 1 is a front assembly view of mechanism embodying my invention.

Figure 2 is a plan view thereof.

Figures 3 and 4 are views of the right and left ends respectively of the parts shown in Figure 2.

Figure 5 is a rear elevation of the mechanism shown in the preceding figures.

Figures 6, 7, 8 and 9 are rear elevations of parts of the mechanism shown in Figure 5, the different views illustrating the parts in their various positions.

Figure 10 is a fragmentary sectional view taken on the line 10—10, Figure 5.

Figure 11 is a plan of the reversing gears and associated parts showing them changed from the position shown in Figure 2.

Figures 12, 13 and 14 are perspective views of the noncalculating cam, adding cam and subtracting cam respectively.

Figures 15, 16 and 17 are detail sectional views taken respectively on the lines 15—15, Figure 1, and the lines 16—16 and 17—17, Figure 5.

Figures 18, 19 and 20 are detail views showing component parts of the mechanism.

Similar numerals refer to similar parts 100 throughout the several views.

In the form of machine selected to illustrate the invention the totalizer "jumps", that is, is caused to travel a limited distance in unison with the typewriter carriage and 105 is then released, returned to original position and again caused to travel in unison with the carriage. It is an object of my invention to provide simple and efficient means for accomplishing this action and also for 110

suspending said action and permitting the carriage to travel without moving the totalizer. In connection with the last named object, it is my purpose to provide means whereby a single lever, herein termed the "disconnecting" lever may perform the double function of disconnecting the typewriter keys from the calculating mechanism and simultaneously disconnecting the totalizer from the mechanism which normally causes it to travel.

The typewriting machine to which the computing mechanism is attached may be of any suitable description. In Fig. 1, I have conventionally represented at A the ten numeral keys of an ordinary typewriter, at B the stationary carriage rail, and at C the front bar of the carriage itself which carriage supports a paper platen D.

The driving sector 1 is secured to the driving sector shaft 2 in such manner as to rotate with said shaft and to swing laterally into and out of mesh with the gear wheel 3 and cause said wheel to rotate always in the same direction an amount dependent upon the value of the figure key struck. The mechanism for causing said sector to rotate and to vibrate laterally is shown to a certain extent in the lower portion of Figures 1 and 5, but as the mechanism has been previously described in Patent Number 893,719, granted to me July 21, 1908 detailed description is unnecessary here. Said wheel 3, which is best shown in Figures 1, 2 and 11, is rigidly secured to a grooved sleeve 4, slideable upon a shaft 5, and is at all times in spline connection with a sleeve 6, which is rigidly attached to said shaft and rigidly secured to the master wheel 7. The result is that the master wheel rotates whenever gear wheel 3 rotates irrespective of the position of said gear wheel laterally upon shaft 5. Said gear wheel remains permanently in mesh with a gear wheel 10 rigidly secured to a sleeve 11, mounted upon a shaft 12 parallel to shaft 5. Sleeves 4 and 11 are circumferentially grooved and engaged by a lever 13 fulcrumed upon a stationary pin 14. Sleeve 11 is rotatable independently of shaft 12 but is adapted to be shifted laterally by said shaft which is slidably mounted in the frame plates 16, 17. The normal position of the parts is shown in Figure 2, and when in this position the sector 1 can engage only the gear wheel 3 which rotates the master wheel 7 in the direction to produce addition in the totalizer 18. When shaft 12 is shifted to the right, Figure 2, it shifts the gear wheel 10 into a position where it can be engaged by the driving sector. This shifting of the gear wheel 10 operates the lever 13 and causes it to shift the gear wheel 3 to a position where it cannot be reached by the sector 1. When the parts are in this position the sector engages the gear wheel 10 which in

turn rotates the gear wheel 3 and the master wheel 7 and causes the latter to rotate in the opposite direction from before and causes the totalizer to subtract. When the shaft 12 is shifted to an intermediate position, as shown in Figure 11, the wheels 3 and 10 both remain out of reach of the driving sector and consequently no motion is transmitted from the latter. This is known as the non-calculating position, the parts normally driven by the driving sector remaining disconnected therefrom and from the rest of the key mechanism.

Shaft 12 is shifted by means of a slotted arm 20, rigidly secured to a rock shaft 21. As shown in detail in Figure 17 said rock shaft enters into and is rigidly secured to a sleeve 22, journaled in the stationary frame piece 23 which is secured to the top plate 23 of the typewriting machine. On the opposite side of said frame piece is a boss 24 which acts as a distance piece, against the end of which bears a rocking plate 25 fast on shaft 21. It is obvious that by rocking said plate in one direction the machine may be caused to add and by rocking it in the opposite direction the machine may be caused to subtract and by rocking it to an intermediate position the machine may be disconnected from the keys, that is, rendered nonoperative. In my machine said plate is controllable in a variety of ways which will first be suggested and later be more fully described:

First, a setting lever is provided which is adapted to occupy three different positions. In one extreme position the totalizer will always add. In the opposite extreme position the totalizer will always subtract, and in intermediate position the rocking plate and therefore the master wheel will be subject to the action of certain controlling cams which will cause the machine to add or subtract or not calculate, depending upon the configuration of the cam temporarily in action. Consequently the setting lever may be said to be capable of producing addition, subtraction or automatic (cam) operation. Second, a correcting lever is provided which is normally non-operative but which, when thrown into acting position, will reverse the direction of rotation of the master wheel irrespective of the direction in which said master wheel would otherwise have rotated. I will first describe the setting lever and parts operated thereby.

Setting mechanism or manual controlling means.

In the present construction said setting lever 26 is mounted at the right end of the machine and is best shown in elevation in Figure 3. It is fulcrumed upon the pin 27 which is rigidly supported in the stationary frame plate 28. Said setting lever, which

is also shown at the right end of Figures 1 and 2 and at the left end of Figure 5 of the drawings, works within a stationary slotted segment 29 which is suitably notched to hold 5 said lever in high, low and intermediate positions, which in the present instance correspond respectively to subtracting, adding and automatic operation of the totalizer. At the rear end the lever is pivoted to a link 31 which in turn is pivoted to a lever 32 fulcrumed upon a stationary pin 33, as best shown in Figures 5, 6 and 8. Said lever 32 has a slot and pin connection 34 with a rocker arm 35 which is pivoted upon a stationary 10 screw 36. Near the free end of said rocking lever is a screw 37 which affords pivotal connection with a cam bar 38 having at its far end a cam whose acting surface may be divided into three portions 38^a, 38^b and 38^c. 15 A slot 38^d is also formed in said cam bar, and through this slot extends a pin 40 rigidly fastened upon the lever 41 which is connected to and operated by the correcting lever in the manner hereinafter described. In the design 20 shown the cam bar moves substantially horizontally when the arm 35 is rocked and the slot 38^d extends parallel to the line of movement of said cam bar, whereby the bar is free to move horizontally but is controlled in a vertical direction by the pin 40. Said pin is raised and lowered by rotating the lever 41 about its stationary fulcrum pin 42 in the manner hereinafter explained. It is sufficient for the present to say that the raising and lowering of the pin 40 brings the cam bar to operative and to non-operative 25 positions respectively.

The cam surfaces 38^a, 38^b and 38^c upon the cam bar are adapted to act upon two pins 45 and 46 projecting from the rocking plate 25 previously referred to. These pins are placed on opposite sides of the center of the rock shaft 21 upon which said plate is supported and the pins are so located as to be actuated by the cam surfaces upon bar 38. The proportion and arrangement is such that when lever 41 holds the cam bar up in acting 30 position a movement of said bar toward the left (Figure 5) will cause the cams on said bar to act upon the pin 45 and rotate said plate in a clockwise direction (Figure 5) and hold it there, the pin 45 first being acted upon by the cam surface 38^a and then being retained in the final position by the cam surface 38^b which lies parallel with the direction of motion of the cam bar. The final position of the cam bar and rocking plate is shown in Figure 8. When the cam bar is moved to the extreme right the cam surface 38^a releases pin 45 while the cam surface 38^c 35 engages the pin 46 and rotates the rocking plate to the opposite position wherein it is held by the cam surface 38^b acting upon pin 46. Thus the lengthwise movement of the cam bar rocks the plate 25 from one extreme

position to the other to change from addition to subtraction and vice versa. When said bar is in intermediate position, as shown in Figure 7, the rocking plate is free to move without interference by said cam bar. 70

When the lever 41 is rotated in such position as to permit the cam end of bar 38 to drop down to non-acting position the rocking plate is out of reach of the cam bar, irrespective of the position of the latter horizontally. 75

Correcting mechanism.

I will now describe the mechanism by means of which the action of the machine 80 may be reversed for making corrections. As previously mentioned, the lever 41 is fulcrumed upon the stationary pin 42. It is pivoted to a link 48 which in turn is pivoted to the correcting lever or key 49 which is 85 adapted to be manually operated. A spring 50 is attached at one end to the stationary frame plate 51 and at the other end to lever 49, the parts being so arranged that spring 50 tends to hold said correcting lever in non-acting position with the lever 41 in the 90 position shown in Figures 5, 7 and 8. If desired the correcting lever may be held down in acting position by a retaining handle 52 pivoted upon the stationary pin 33 95 and provided with a hook 54 adapted to engage a shoulder 55 which is rigid with the correcting lever. These parts are in this instance located at the left end of the machine when viewed from the front, and are best shown in Figure 4. 100

Pivottally connected to lever 41 by means of a pin 57 is a dog 58 which in the form shown is approximately anchor shaped and provided with two hooks 59 and 60 adapted to engage respectively the pins 45 and 46 upon the rocking plate 25. Dog 58 which is shown separately in Figure 18 is arranged between lever 41 and plate 25 and is laterally controlled by a pin 62 secured to plate 25 and passing through a triune slot in said dog. Said slot has two lateral branches 63 and 64 and a downwardly extending vertical branch 65. When the parts are in the position shown in Figure 7 with the correcting lever in normal non-acting position the dog will be elevated and therefore be non-active, and will be held in central position by the pin 62 which will be in said vertical branch 65; but when plate 25 is rocked to the position to elevate pin 45, as shown in Figure 8, the pin 62 will throw the dog 58 over toward said pin so that when said dog is depressed by the lowering of pin 57 the hook 59 of said dog will engage said pin 45 and rock plate 25 to the opposite position, shown in Figure 9. This lateral movement of the dog is permitted by reason of the space afforded to pin 62 by the lateral branch 64 in 110 said dog. In a similar manner if, from the 115

central position shown in Figure 7, the plate 25 be rocked to a position to elevate pin 46 as shown in Fig. 5, the pin 62 in the vertical branch 65 will swing the dog over toward 5 pin 46 so that when said dog is depressed by the action of lever 41 the hook 60 of the dog will engage the pin 46 on the rocking plate and reverse the position of said plate, as shown in Figure 6. From the foregoing 10 it will be clear that the act of operating the correcting lever 49 (which causes the pin 57 to descend) will cause the dog to act upon the rocking plate 25 in such manner as to reverse the latter and thereby change the 15 machine from a condition to add to a condition to subtract or vice versa.

In Fig. 8 the machine is shown set for subtraction by the cam 38^a, 38^b. When by the depression of the correction key 49 the 20 parts are moved from the Fig. 8 to the Fig. 9 position the guide pin 40, being mounted on the lever 41, moves downward and moves the cam part 38^b away from pin 45 allowing the latter to be depressed by the hook 58, 25 thus setting the machine for addition. When the key 49 is released and the lever 41 is restored by the spring 50 to its normal position the cam bar 38 again moves upward and the cam part 38^b acting on pin 45 restores 30 the parts to subtraction as shown in Fig. 8. The reversal effected by the key 49 therefore lasts only as long as said key is held in its depressed position, the parts being immediately restored when the key is released. 35 The key or lever 49 is herein called a correcting key or lever, this being a convenient designation therefor and expressing one of the principal uses of said key. It will be obvious however that said key or lever can 40 be used on any occasion when it is desired to make the machine do the opposite of that for which it was primarily set.

Automatic cam operation.

45 I have already described how the rocking plate 25 may be rocked to and held in adding or subtracting position as desired by the setting lever 26. I will now describe how said plate may be operated by cams and 50 automatically be rocked to adding position or subtracting position or non-operating or non-calculating position:

According to the present design the machine is brought to automatic, cam operative 55 condition by bringing the setting lever 26 to intermediate position, as shown in Figures 1, 3, 5, 6 and elsewhere. A link 66 is pivoted at one end to the rocking plate 25 and at the other end to a link 67 which is pivoted at its 60 ends to levers 68 and 69 fulcrumed respectively upon pins 70 and 71 upon a fulcrum plate 72 which latter is shown separately in Figure 19. At their free ends said levers 65 are provided with antifriction rollers 73 and 74 respectively adapted to be engaged

and operated by the controlling cams which will presently be described. Plate 72 has three vertical guide slots 76 which receive the pins 77 which screw into the stationary frame plate 23. Said pins project through the slots 70 in said fulcrum plate and permit it to move in a vertical direction. The position of the fulcrum plate vertically is controlled by a pin 78 which projects from said plate through a slot 79 in the lever 80, shown in 75 Figures 5 to 9 and separately in Figure 20. Said lever is fulcrumed upon a pin 81 screwing into the frame plate 23. A spring 83 is fastened at one end to said lever and at the other end to frame plate 23 in such manner 80 as to normally hold the pin 78 and fulcrum plate in raised position where the levers 68 and 69 can be operated upon by the controlling cams 85, 86 and 87, shown separately in perspective in Figures 12, 13 and 14 respectively. The relation of these cams to the rollers and their levers is shown in Figure 7.

Said cams are adjustably mounted upon a horizontal cam bar 88 which travels in unison with the typewriter carriage. The most common practice in typewriters is to so construct the escapement that the carriage will travel one tenth of an inch at each step. In my machine I make apertures in the cam bar 95 three tenths of an inch apart and make apertures in the cams one tenth of an inch apart; hence the cams may be adjusted every tenth of an inch along the bar and yet the bar is only penetrated once for every three tenths of an inch. This reduces the amount of drilling necessary and correspondingly conserves the strength of the bar.

In the preferred form here shown, the main body of each cam is in the form of a saddle resting upon the bar so as to engage it back and front, as best shown in the upper portion of Figures 3 and 16. The rollers 73 and 74 are located one behind the other and the cams therefore travel in different parallel paths. The cam 86, which is the "adding" cam, shown separately in Figure 13, has at the back an acting surface 86^a adapted to engage and depress the roller 73 on the adding lever 68. When this action takes place said adding lever will be rotated in a clockwise direction (Figure 5) and will move the link 67 towards the left, thus moving the link 66 toward the left, and rocking the plate 25 to adding position. The subtracting cam 87, shown separately in Figure 14, has attached to the back thereof an acting cam 87^a which is adapted to engage and depress the roller 74 on the subtracting lever 69 and thus rock the plate 25 to subtracting position. The "non-calculating" cam 85 has an acting surface 85^a adapted to engage the roller 73 and an acting cam 85^b adapted to 110 simultaneously engage the roller 74. The acting edges 85^a and 85^b of the non-calculat- 115 120 125 130

ing cam 85 are at the same level and the parts are so constructed that when the non-calculating cam is in action it will hold the rollers 73 and 74 at the same level and thus hold the links 67 and 66 and the rocking plate 25 in intermediate position, as shown in Figure 7. Under such conditions the gear wheels 3 and 10 will both be held out of the reach of the driving sector 1, as shown in Figure 11. It will thus be plain that when my machine is set for automatic or cam operation with the setting lever 26 in intermediate position the machine will add, subtract, or not calculate in any given column, depending upon the adjustment of the cams.

The control of the cam mechanism by the setting lever.

When the fulcrum plate is in elevated acting position the controlling cams operate positively, there being no yield between them and the rocking plate 25. I will now describe means for withdrawing the fulcrum plate and crank levers from acting position, so that the machine may be set in position to add or subtract without being influenced by the controlling cams. I have already mentioned that the position of the fulcrum plate 72 vertically is controlled by the lever 80 which, for identification, may be referred to as the "selector" lever. This lever, which is shown separately in Figure 20, has a wavy cam on its under edge having three controlling points 80^a, 80^b, 80^c. A roller 35^a, shown in dotted lines in Figures 5, 6 and 8, is carried at the lower extremity of the rocker arm 35 in position to engage this cam edge upon said lever and to rotate said lever about its fulcrum 81 when said arm is rocked. When the rocker arm is at the left (Figure 8) and the roller 35^a is in contact with the acting point 80^a the fulcrum plate will be held down in non-acting position and the cam bar 38 will hold the rocker plate 25 in subtracting position, all as shown in Figure 8, and hence the point 80^a may be considered as the "subtracting" point on said lever. When said roller is in contact with the point 80^c the selector lever 80 will be in substantially the same position and will hold the fulcrum plate down but the cam bar 38 will hold the rock plate 25 in the adding position and hence the point 80^c may be considered as the "adding" point. The point 80^b is located between the points 80^a and 80^c and is so placed upon the lever 80 that when the roller 35^a is in contact therewith the fulcrum plate 72 will be in elevated, active position, as shown in Figure 7, and hence the point 80^b may be considered the "automatic" or "cam operating" point. From this it will be seen that the setting lever 26 operates not only the cam bar 38 to positively rock the rocking plate 25 but also operates the selector lever to thereby

control the position of the fulcrum plate 72 for whatever operation may be contemplated.

Cam mechanism acted upon by correcting lever.

The selector lever 80 is operable not only by the roller 35^a but also by the lever 41 controlled by the correcting lever 49. As previously stated, it is the function of the correcting lever to reverse the direction of rotation of the master wheel. To render this possible I have provided a pin 90 upon the lever 41 in position to engage the upper edge of the selector lever 80 in such manner that when the correcting lever is moved down to acting (correcting) position, as shown in Figure 6, it will depress the adjacent end of the selector lever and draw down the fulcrum plate so that the levers thereon will be out of reach of the controlling cams, as shown in Figure 6. Under normal conditions when the correcting lever is non-acting the pin 90 will be elevated and permit the adjacent end of the lever 80 to rise if otherwise free to do so. Under these conditions the position of the parts is shown in Figure 7. It will be perceived that the setting of the change gears 3 and 10 by the shaft 12 corresponds not with any definite actual elevation of said followers 73 and 74 but with the relative elevations of said followers. Whenever the shaft 12 occupies its left-hand position corresponding to addition the roller 74 occupies a higher position than the roller 73 as shown for example in Fig. 9. In this figure the parts were set for addition by means of the correcting lever and the followers 73 and 74 both occupy depressed positions but they occupy the same relative positions that they do in Fig. 5 where the machine is under cam control and the setting is for addition. The combination of two followers so connected that they control the addition of the computing mechanism by their relative positions, said followers pressed against their controlling cams by the spring 83, has marked advantages over other means of cam control. If for example in Fig. 5, the carriage be pulled back to the right the subtract cam 87 will push the follower roller 74 down until said roller bears against the under side of the cam. This will force shaft 12 leftward as far as said shaft will go. If there is any excess of downward motion forced by the cam this will be taken up by simply stretching the spring 83. When the disconnect cam runs over the followers as shown in Fig. 7 a similar thing may occur. The two cam edges 85^a and 85^b compel the two rollers to occupy the same elevation. This will set the machine for disconnect regardless of any slight motion that the followers and their supporting means may be compelled to have together. In

other words, the cam 85 may occupy so low a position as to slightly stretch the spring 83. One advantage of this construction is that it obviates the necessity for any great precision in the up and down position of the bar 88. This bar is mounted on the typewriter carriage and if it were necessary to make it travel right and left in such a way that its up and down position was always guided with precision this would be an expensive and difficult thing to do. With the present construction it is only necessary to see to it that this bar is low enough. It can be a little too low without any harm and no harm will be done if it is a little lower at one end than it is at the other, the only difference caused by such lack of precision being in the extent to which the spring 83 will be stretched. Moreover, if by any accident the shaft of the change gear mechanism should be blocked the mechanism would not be injured. In that event the whole action of the cams on the followers would consist in stretching the spring 83.

25

Operation.

The first option afforded the operator is whether he desires the machine to calculate and print or merely to print without calculating. This option is afforded by mechanism shown in my previous patent, and, therefore, may for the moment be disregarded. It may be assumed that the operator wishes the machine in calculating condition. Under these circumstances the correcting lever 49 will normally remain raised, as shown in Figures 4, 5, 7 and 8, and will have no influence upon the parts of the machine which are acting. The operator now has the option as to whether he wishes the machine to add or subtract or to be controlled automatically by the controlling cams 85, 86, 87. If he wishes the machine to subtract he throws the setting lever 26 up, thereby bringing the parts to the positions shown in Figure 8 with the cam bar holding the locking plate 25 in subtracting position and the selector lever 80 holding the fulcrum plate 72 down in non-acting position. If he wishes the machine to add he throws the setting lever down to the opposite end of its movement, thus reversing the position of the cam bar and rocking plate, and bringing the roller 35^a from the acting point 80^a to the acting point 80^c on the selector lever 80 but leaving said lever and the fulcrum plate in the same position as before, that is, the non-acting position. If the operator wishes the machine to be cam operated he brings the setting lever to intermediate position, shown in Figure 3, thus bringing the cam bar 38 to intermediate position where it will not interfere with the rocking plate 25 and simultaneously bringing the roller 35^a to intermediate position where it will contact the

acting point 80^b of the selector lever and permit the spring 83 to hold the fulcrum plate elevated in acting position. The parts will then occupy the position shown in Figure 7.

70

The operator now adjusts the controlling cams 85, 86, 87 to the proper positions upon the cam bar 88 to produce the kinds of calculation wanted in the various columns. The cams will then automatically set the machine to add, subtract or not calculate, according to the configuration of the particular cam at the acting point above the levers 68 and 69.

75

If at any time the operator discovers that he has struck a wrong figure key he immediately depresses the correcting lever 49. This lowers the pin 90 on the lever 41 and causes the fulcrum plate 72 and levers thereon to be drawn down out of acting position. It also causes the downward movement of the pin 57 in lever 41 which draws downward the dog 58, thus causing it to reverse the position of the rocking plate 25. The operator then merely has to strike the same figure key over again, whereupon the effect of the original incorrect striking will be neutralized. If the incorrect figure were added the correcting lever will cause it to be subtracted and vice versa. It will be noted that it is unnecessary for the operator to observe whether the machine was adding or subtracting when the mistake was made. The reversal will take place automatically upon the depression of the correcting lever.

105

Disconnecting mechanism.

The totalizer 18 previously mentioned is slidingly supported upon two bars 92 (Fig. 1) which are arranged parallel to the travel of the typewriter carriage and are supported in flanges 23^a of the stationary frame plate 23. Said flanges are connected by a yoke piece 93 which carries a pointer 93^a to indicate the operating point in the totalizer. The totalizer is constantly urged toward the right (Figure 1) by a tension spring 94. Two cushion springs 95, coiled around the bars 92, minimize the shock when the totalizer is released and moves toward the right under the influence of spring 94. Extending rearwardly from the totalizer is a bar 96, best shown in Figure 16. Said bar is pivoted on a pin 97 journaled in the walls of the totalizer and is urged by a spring 98 in such manner as to normally hold its rear end elevated in position to be engaged by the lugs 99 formed at the lower edge of the front side of the controlling cams 85, 86, 87 (Figs. 1, 3 and 16). Said lugs are so formed that when they and the typewriter carriage are moving in a forward (leftward) direction (Fig. 5) they will engage the rear end of the bar 96 but will depress and pass over said bar when the typewriter carriage is be-

110

115

120

130

ing returned to initial position. To the left of the totalizer (Figure 1) a releasing cam 100 is screwed to the frame plate 23 and is provided with a working edge 100^a so formed that when the bar 96 comes into contact therewith, as a result of the travel of the totalizer under the influence of the lugs 99, said bar will be depressed far enough to release it from engagement with the acting lug 99 and thereby permit the spring 94 to return the totalizer to the right. As soon as the bar is released from the acting lug and from the releasing cam it automatically rises under the influence of the spring 98 and assumes a position where it may be engaged by the next succeeding lug 99. The totalizer will thus be brought back for each complete number, so that all the numbers occurring in the same horizontal line may be entered into the same totalizer if desired.

I have provided means whereby the jumping totalizer may remain stationary at the initial position if desired, thus permitting the machine to operate as a typewriter without the burden of moving the totalizer. This is accomplished by an arm 101 which is fulcrumed upon a pin 101^a rigidly carried by the frame plate 23, as shown in Figures 1, 2 and 16. Said arm has a portion which overlies bar 96 in such manner that when said arm is rotated in an anti-clockwise direction (Figure 1) it will hold said bar clear of the passing lugs 99. Said arm is operated by a link 102 which is operated by an arm 103 pivoted upon the stationary screw 104, as shown near the left central portion of Figure 1. Said arm 103 is also shown in Figure 15. A projection 103^a extends toward the left from arm 103 and is engaged within a slot 105, formed in the disconnecting lever 106. Said lever is fulcrumed upon the stationary pin 107 and the parts are so arranged that when the front handle portion of said disconnecting lever is depressed it will rotate the arm 103 in a clockwise direction (Figure 1) and move link 102, toward the right and cause the arm 101 to push the bar 96 down into non-acting position. Thus whether the totalizer will travel or not depends upon the position of the disconnecting lever 106.

In my machine said disconnecting lever performs a double function, to-wit, first the function just described in controlling the position of the totalizer bar 96, and, second, the "disconnecting" of the driving sector 1; that is, preventing said driving sector from reaching either of the gears 3 or 10 irrespective of the position of said gears. The mechanism whereby this second function is accomplished is not new, having been fully described in my Patent 893,719 previously referred to. It will therefore be sufficient for the purpose to say that the disconnecting lever which is normally held down by the spring 108 (Figure 15) corresponds to the

disconnecting lever 160 in my said patent and that the rock shaft 110 which corresponds to the shaft 91 in my said patent is hung from the stationary shaft 111 which is marked 89 in said patent. The rock shaft 110 of my present machine controls the driving sector in the same manner as the rock shaft does in my said patent, while the sector shaft 112 in my present drawings corresponds to and performs the same function as the shaft 69 in my said patent.

Operation:

In the operation of the disconnecting lever 106 and parts operated thereby, when the operator does not wish to use the calculating parts of the typewriter he pulls the lever 106 down, thereby accomplishing two things, first, raising the rock shaft 110, thus rendering the driving sector 1 ineffective; and second, causing the arm 101 to hold the totalizer bar 96 out of the path of the lugs 99, and consequently permitting the totalizer to remain stationary.

In some of the claims expressions are used such as "the state of the computing mechanism." By this is meant the condition of said mechanism with respect to the operation it is set to perform, as addition or subtraction.

Having thus described my invention, what I claim as new and desire to secure by Letters Patent is:

1. A calculating machine, having a totalizer adapted to add and subtract, and both automatic and manually operated controlling mechanisms for changing from addition to subtraction and vice versa; the manually operated controlling mechanism being adapted, when put in acting condition, to render the automatic controlling mechanism ineffective.
2. In a calculating machine the combination of a totalizer, master mechanism therefor, and two different controlling means for determining whether said master mechanism shall cause addition or subtraction, one of said controlling means being non-operative when the other is operative and vice versa.

3. In a calculating machine the combination of a totalizer, master mechanism therefor, two different controlling means for determining whether said master mechanism shall cause addition or subtraction, and means for rendering one of said controlling mechanisms non-operative when the other is operative.

4. In a calculating machine the combination of a totalizer, actuating means therefor, and controlling means for controlling said actuating means to thereby determine whether said actuating means shall cause addition or subtraction, said controlling means comprising automatic cam mechanism and

manually operated mechanism, the manually operated mechanism being adapted to dominate said cam mechanism and render it non-active.

5. In a calculating machine the combination of a totalizer, master mechanism therefor, automatic controlling means adapted to determine whether said master mechanism shall add or subtract, and hand operated controlling means also adapted to determine whether said master mechanism shall add or subtract, said hand operated controlling means being adapted to render the automatic controlling means ineffective, where-
15 by the automatic control may be temporarily suspended when desired.

6. In a calculating machine the combination of a totalizer, master mechanism for actuating the same, and two different controlling means for determining whether said master mechanism shall cause addition or subtraction, one of said controlling means being automatic and the other manual, the automatic controlling means being adapted
20 to be rendered non-operative when the manual controlling means is operative and vice versa.

7. In a calculating machine the combination of a totalizer, master mechanism therefor, cam operated controlling means for causing said master means to add or subtract, other controlling means for causing said master means to add or subtract, and a handle for rendering a predetermined one
30 of said controlling means controlling upon the master mechanism.

8. In a calculating machine the combination of a totalizer, master mechanism therefor, two different controlling mechanisms, each of which are adapted to cause the master mechanism to produce either addition or subtraction, and a handle adapted to actuate one of said controlling mechanisms and simultaneously render the other one
40 non-operative.

9. In a calculating machine the combination of a totalizer, actuating means therefor, and controlling means for controlling said actuating means to thereby determine whether said actuating means shall cause addition or subtraction, said controlling means comprising two automatically operative levers and a manually operative lever, the manually operative lever being adapted
50 to render the automatically operative levers non-operative.

10. In a calculating machine the combination of a totalizer, master mechanism therefor, cam operated means for causing said master mechanism to either add or subtract or not operate, a handle connected to said cam operated means for rendering the same operative or non-operative, and other means operated by said handle for causing said
60 master mechanism to add or subtract.

11. In a calculating machine the combination, with a traveling carriage, of a totalizer, master mechanism therefor, controlling means for causing addition, subtraction or non-operation of the totalizer, two different
70 mechanisms for operating said controlling means, one being automatic and the other non-automatic, the automatic mechanism being cam operated by the movement of the carriage, and a handle adapted to operate
75 the non-automatic mechanism and at the same time control the automatic mechanism and render the latter non-operative when the non-automatic mechanism is in condition to cause either addition or subtraction.
80

12. In a calculating machine the combination, with a traveling carriage, of a totalizer, master mechanism therefor, controlling means for changing from addition to subtraction and vice versa, cam mechanism operated by the carriage for operating said controlling means, and manually operated means operative upon the cam mechanism for rendering the parts thereof cooperative or temporarily non-cooperative.
85

13. In a calculating machine the combination of a totalizer, master means therefor, controlling means for changing from addition to subtraction and vice versa, a pair of levers connected to said controlling means
90 for operating the same, traveling cams for operating said levers and manually operated means for determining whether or not said levers shall come within the path of said cams to be operated thereby.
100

14. In a calculating machine the combination of a totalizer, master means therefor, controlling means for changing from addition to subtraction and vice versa, a pair of levers connected to said controlling means
105 for operating the same, traveling cams for operating said levers, spring means tending to move said levers bodily into the paths of said cams for being operated by said cams, and manually operated means for holding
110 said levers out of the paths of said cams.

15. In a calculating machine the combination of a totalizer, master means therefor, controlling means for changing from addition to subtraction and vice versa, a pair of levers connected to said controlling means
115 for operating the same, traveling cams for operating said levers, a movable plate whereon said levers are fulcrumed, and a handle for controlling the position of said plate to thereby determine whether said cams shall or shall not be in position to be operated by said cams.
120

16. In a calculating machine the combination of a totalizer, master means therefor, controlling means for changing from addition to subtraction and vice versa, a pair of levers connected to said controlling means
125 for operating the same, and a traveling cam for actuating each of said levers.
130

17. In a calculating machine the combination of a totalizer, master means therefor, controlling means for changing from addition to subtraction and vice versa, a pair of levers connected to said controlling means for operating the same, and two traveling complementary cams, one for each lever, one cam being located behind the other, whereby the second cam engages its lever after the first cam has passed beyond its lever. 70
18. In a calculating machine the combination of a totalizer, master means therefor, controlling means for changing from addition to subtraction and vice versa, a pair of levers connected to said controlling means for operating the same, a pair of complementary cams, one for each lever and adapted to engage them successively and means for causing relative travel between the levers and the cams. 75
19. In a calculating machine having in combination a totalizer, master means therefor, controlling means for changing from addition to subtraction and vice versa, a lever connected to said controlling means for operating the same, a traveling bar having a step by step movement, and a cam mounted upon said bar and adapted to operate said lever, said cam having a plurality of apertures located one step apart, and said bar having a plurality of apertures located at a plurality of steps apart, the apertures on the cam being adapted to register with the apertures on the bar for permitting adjustment of the cam upon the bar. 80
20. In a calculating machine having in combination a totalizer, master means therefor, controlling means for changing from addition to subtraction and vice versa, a pair of levers connected to said controlling means for operating the same, a traveling bar having a step by step movement, and a double cam mounted upon said bar and adapted to engage said levers simultaneously, said cam having a plurality of apertures located one step apart and said bar having a plurality of apertures located at a plurality of steps apart, the apertures on the cam being adapted to register with the apertures on the bar. 85
21. In a calculating machine the combination of a totalizer, a master gear therefor, a driving sector, reversing gearing for transmitting motion from said sector to said master gear, controlling means for controlling said reversing gearing, a lever connected to said controlling means for operating the same, a cam for operating said lever, and means for causing relative travel between said lever and cam to thereby cause the cam to operate the lever. 90
22. In a calculating machine the combination with a totalizer, a master gear therefor, a rotary and laterally vibratile driving sector, reversing gearing for transmitting motion from said sector to said master gear, and controlling means for controlling said reversing gearing, of a pair of levers connected to said controlling means for operating the same, a pair of complementary cams, one adapted to engage one of said levers while the other cam is engaging the other, and means for causing relative travel between said levers and said cams. 95
23. In a calculating machine the combination, with a traveling carriage, of a totalizer, master means therefor, controlling means for changing from addition to subtraction and vice versa, a setting handle, and two cam mechanisms for operating said controlling means, one of said cam mechanisms being automatic and operated by the motion of the carriage and the other of said cam mechanisms being operated by said handle, and means operated by said handle for rendering the automatic cam mechanism non operative when the non automatic cam is moved to acting position. 100
24. In a calculating machine the combination, with a traveling carriage, of a totalizer, master means therefor, controlling means for changing from addition to subtraction and vice versa, automatic cam mechanism operated by the movement of the carriage for operating said controlling means, a setting handle, and a cam operated by said handle and adapted to operate said controlling means. 105
25. In a calculating machine the combination, with a traveling carriage, of a totalizer, master means therefor, controlling means for changing from addition to subtraction and vice versa, automatic cam mechanism operated by the movement of the carriage for operating said controlling means, a setting handle, a cam bar operated thereby and adapted to engage and operate said controlling means, and means operated by said handle for rendering the automatic cam mechanism nonoperative when said cam bar is in engagement with said controlling means. 110
26. In a calculating machine the combination of a totalizer, master means therefor, controlling means for changing from addition to subtraction and vice versa, and a movable cam adapted to engage and operate said controlling means, said cam being capable of occupying three positions, in the first position moving said controlling means to one condition, in the second position moving said controlling means to opposite condition and in the third position clearing said controlling means and leaving it free to be moved. 115
27. In a calculating machine the combination of a totalizer, master means therefor, controlling means for changing from addition to subtraction and vice versa, a setting handle, and two cam mechanisms for operating said controlling means, one of said cam mechanisms being automatic and operated by the motion of the carriage and the other of said cam mechanisms being operated by said handle, and means operated by said handle for rendering the automatic cam mechanism non operative when the non automatic cam is moved to acting position. 120
28. In a calculating machine the combination, with a traveling carriage, of a totalizer, master means therefor, controlling means for changing from addition to subtraction and vice versa, automatic cam mechanism operated by the movement of the carriage for operating said controlling means, a setting handle, a cam bar operated thereby and adapted to engage and operate said controlling means, and means operated by said handle for rendering the automatic cam mechanism nonoperative when said cam bar is in engagement with said controlling means. 125
29. In a calculating machine the combination with a totalizer, a master gear therefor, a driving sector, reversing gearing for transmitting motion from said sector to said master gear, controlling means for controlling said reversing gearing, a lever connected to said controlling means for operating the same, a cam for operating said lever, and means for causing relative travel between said lever and cam to thereby cause the cam to operate the lever. 130

- tion to subtraction and vice versa, a manually operated movable cam adapted to engage and operate said controlling means, said cam being capable of occupying three positions, 5 in the first position moving said controlling element to one condition, in the second position moving said controlling means to opposite condition, and in the third position clearing said controlling means and leaving 10 it free to be moved, and automatic cam mechanism adapted to operate said controlling means when the latter is free to be moved.
28. In a calculating machine the combination with the traveling carriage of a totalizer, master means therefor, controlling means comprising a rock member and connections therefrom to the master means for changing from addition to subtraction and vice versa when said rock member is rocked, 15 20 a manually operated movable cam adapted to rock said rock member, and cam mechanism operated by the movement of the carriage and adapted to rock said rock member.
29. In a calculating machine the combination, with a traveling carriage, of a totalizer, master means therefor, controlling means comprising a rocker and connections therefrom to the master means for changing from addition to subtraction and vice versa 25 30 when said rocker is rocked, a manually operated movable cam adapted to rock said rocker and capable of occupying three positions, in the first position holding said rocker in position for addition, in the second position holding said rocker in position for subtraction, and in the third position clearing said rocker and leaving it free to move, and cam mechanism operated by the movement of the carriage and adapted to rock said rocker.
- 40 30: In a calculating machine the combination, with a traveling carriage, of a totalizer, master means therefor, controlling means comprising a rocker and connections therefrom to the master means for changing from 45 addition to subtraction and vice versa when said rocker is rocked, a movable cam bar adapted to rock said rocker and capable of occupying three positions, in the first position holding said rocker in position for addition, in the second position holding said rocker in position for subtraction, and in the third position disengaging said rocker and leaving it free to move, automatic cam mechanism operated by the movement of the carriage and adapted to rock said rocker, and a handle connected to said cam bar for operating it and also connected to said automatic cam mechanism for rendering the latter non-operative when the cam bar is in engagement with said rocker.
- 50 31. In a calculating machine the combination with a traveling carriage of a totalizer, master means therefor, controlling means comprising a rocker and connections therefrom to the master means for changing from 55 60 addition to subtraction and vice versa, automatic cam mechanism operated by the travel of the carriage for operating said rocker, a setting handle, a cam operated by said setting handle for operating said rocker, a correcting handle, and means operated by said correcting handle for operating said rocker.
32. In a calculating machine the combination of a totalizer, master means therefor, controlling means for holding the machine 70 in non-calculating condition, two levers connected to each other and to said controlling means for operating it, and two traveling cams rigidly connected together and adapted to engage said levers simultaneously for 75 80 operating them in correspondence with each other.
33. In a calculating machine the combination of a totalizer, master means therefor, controlling means for holding the machine 85 in non-calculating condition, two levers connected to each other and to said controlling means for operating it, and two cams rigidly connected together and located on the same side of said levers and adapted to engage them simultaneously.
34. In a calculating machine the combination of a totalizer, master means therefor, controlling means for changing from addition to subtraction and vice versa, two levers connected to each other and to said controlling means for operating it, two cams traveling in unison and adapted to engage said levers successively, each cam being adapted 95 to engage only its respective lever, and manually operated means for determining whether or not said levers shall extend into the path of the cams.
35. In a calculating machine the combination of a totalizer, master means therefor, controlling means for changing from addition to subtraction and vice versa, two levers connected to each other and to said controlling means for operating it, two traveling cams located upon the same side of said levers and adapted to engage them successively, and manually operated means for determining whether or not said levers shall extend into the path of the cams.
36. In a calculating machine the combination of a totalizer, master means therefor, controlling means for changing from addition to subtraction and vice versa, two levers connected to said controlling means for operating it, two cams traveling in different paths and connected together and adapted 100 105 110 to operate said levers, said levers normally extending into the path of the cams, and manually operated means for holding said levers out of the path of the cams.
37. In a calculating machine the combination of a totalizer, master means therefor, controlling means for changing from addition to subtraction and vice versa, two bell 115 120 125 crank levers connected to said controlling

means for operating the same, and two cams traveling in unison in different parallel paths, said levers being connected together and said cams being adapted to engage said cams successively for the purpose described.

38. In a calculating machine the combination of a totalizer, master means therefor, controlling means for changing from addition to subtraction and vice versa, a movable fulcrum plate, two levers fulcrumed upon said plate, said levers being connected to each other and to said controlling means for operating the latter, traveling cams adapted to engage said levers simultaneously and manually operated means for controlling the position of said plate to thereby determine whether or not said levers shall extend into the path of the cams.

39. In a calculating machine the combination of a totalizer, master means therefor, controlling means for changing from addition to subtraction and vice versa, a lever connected to said controlling means for operating it, a cam, means for causing relative travel between said lever and said cam, a setting lever connected to the first lever for determining whether or not it shall be operated by the cam when said relative travel occurs, and manually operated means for operating said setting lever.

40. In a calculating machine the combination of a totalizer, master means therefor, controlling means for changing from addition to subtraction and vice versa, a lever connected to said controlling means for operating it, a cam, means for causing relative travel between said lever and said cam, a selector lever connected to the first lever for moving it into and out of cooperative relationship with said cam, a cam surface upon said selector lever, a rocker arm adapted to engage the cam surface upon said selector lever to operate said selector lever when said arm is rocked, and means for rocking said arm.

41. In a calculating machine the combination of a totalizer, master means therefor, controlling means for determining whether the machine shall add, subtract, or not operate, a manually operated cam adapted to operate said controlling means and capable of occupying three positions, in the first position holding said controlling means in condition to add, in the second position holding said controlling means in condition to subtract, and in the third position clearing said controlling means and permitting the same to move freely, and other means for operating said controlling means when the same is disengaged from said cam.

42. In a calculating machine the combination of a totalizer, master means therefor, controlling means for determining whether the machine shall add, subtract, or not operate, a manually operated cam adapted to

operate said controlling means and capable of occupying three positions, in the first position holding said controlling means in condition to add, in the second position holding said controlling means in condition to subtract, and in the third position clearing said controlling means and permitting the same to move freely, and two other mechanisms, one automatic and the other manually operated for operating said controlling means when the same is disengaged from said cam.

43. In a calculating machine the combination of a totalizer, a master gear therefor, a driver, reversing gearing for transmitting motion from said driver to said master gear, a rocker adapted to control said reversing gearing, projections on said rocker, a movable cam adapted to engage said projections, said cam being capable of occupying three positions, in the first position holding said rocker in position to produce addition, in the second position holding said rocker in position to produce subtraction, and in the third position leaving the rocker free, and means in addition to said cam for operating said rocker when the latter is free.

44. In a calculating machine the combination of a totalizer, a master gear therefor, a driver, reversing gearing for transmitting motion from said driver to said master gear, a rocker adapted to control said reversing gearing, projections on said rocker, a movable cam adapted to engage said projections, said cam being capable of occupying three positions, in the first position holding said rocker in position to produce addition, in the second position holding said rocker in position to produce subtraction, and in the third position leaving the rocker free, a lever connected to said rocker for operating it when it is free to move, and a second cam for operating said lever.

45. In a calculating machine the combination of a totalizer, a master gear therefor, a driver, reversing gearing for transmitting motion from said driver to said master gear, a rocker adapted to control said reversing gearing, projections on said rocker, a movable cam adapted to engage said projections, said cam being capable of occupying three positions, in the first position holding said rocker in position to produce addition, in the second position holding said rocker in position to produce subtraction, and in the third position leaving the rocker free, a dog adapted to engage said rocker for operating it when it is free to move, and means for operating said dog.

46. In a calculating machine the combination of a totalizer, a master gear therefor, a driving sector, reversing gearing for transmitting motion from said sector to said master gear, a rocker adapted to control said reversing gearing, pins on said rocker, and a

manually operated cam adapted to engage said pins, said cam being capable of occupying three positions, in the first position holding said rocker in position to produce addition, in the second position holding said rocker in position to produce subtraction, and in the third position disengaging said pins and leaving the rocker free, a traveling cam, and a lever operated by said traveling cam, and connected to said rocker for operating the same when it is free to move.

47. A calculating machine adapted both to add and to subtract, and having controlling means for changing from addition to subtraction and vice versa, a pair of projections upon said controlling means whereby the latter may be operated, a correcting lever, a dog operated by said lever, and means for swinging said dog into position to engage one or the other of said projections to thereby reverse the machine.

48. A calculating machine adapted both to add and to subtract, and having controlling means for changing from addition to subtraction and vice versa, a pair of projections upon said controlling means whereby the latter may be operated, a dog adapted to swing laterally to engage one or the other of said projections, means operated by said controlling means for swinging said dog into position to engage the projection which will reverse the machine, and correcting means for moving said dog longitudinally to thereby cause it to move said projection and reverse the machine.

49. In a calculating machine the combination of a totalizer, master means therefor, controlling means for changing from addition to subtraction and vice versa, said controlling means comprising a rocker and projections on said rocker, the parts being so related that when one projection is raised the machine is set for addition and when the other one is raised the machine is set for subtraction, a dog, means for depressing said dog, and means for causing said dog when descending to engage the projection which is raised.

50. In a calculating machine the combination of a totalizer, master means therefor, controlling means for changing from addition to subtraction and vice versa, said controlling means comprising a rocker, and projections on said rocker, the parts being so related that when one projection is raised the machine is set for addition and when the other one is raised the machine is set for subtraction, a dog, and means comprising a correcting handle and connections for depressing said dog, said rocker being adapted to shift the dog laterally to cause it when descending to engage the projection which is raised.

51. In a calculating machine the combination of a totalizer, master means therefor, a

rocker, means operated by said rocker for controlling the action of the machine, a dog for operating said rocker, manually operated means for actuating said dog and means, part of which is on said rocker for shifting the dog and causing it when actuated to reverse the rocker.

52. In a calculating machine the combination of a totalizer, master means therefor, a rocker, means operated by said rocker for causing the machine to be changed from addition to subtraction or vice versa when said rocker is rocked to reverse position, a dog adapted to engage said rocker, means for actuating said dog, and means operated by said rocker for shifting said dog to cause it to engage different parts of said rocker to thereby reverse said rocker when the dog is actuated.

53. In a calculating machine the combination of a totalizer, master means therefor, a rocker, means operated by said rocker for determining whether the master means shall cause addition or subtraction, a manually operated lever, a dog pivoted to said lever and means operated by said rocker for causing said dog to reverse said rocker when the manually operated lever is actuated.

54. In a calculating machine the combination of a totalizer, master means therefor, a rocker, means operated by said rocker for determining whether the master means shall cause addition or subtraction, two projections on said rocker, a dog adapted to engage said projections one at a time to reverse said rocker, manually operated means for actuating said dog, and means, part on the dog and part on the rocker, for causing said dog to engage the projection which is most advanced, whereby when the dog is actuated it will reverse the rocker.

55. In a calculating machine the combination of a totalizer, master means therefor, a rocker, means operated by the rocker for determining whether the master means shall cause addition or subtraction, pins projecting from said rocker, a dog having hooks adapted to engage the pins on said rocker one at a time to reverse said rocker, a manually operated lever whereto said dog is connected, and a slot and pin connection between the dog and the rocker for determining which pin on the rocker the dog shall engage.

56. In a calculating machine the combination of a totalizer, master means therefor, a rocker, means operated by the rocker for determining whether the master means shall cause addition or subtraction, a dog having hooks adapted to engage different portions of said rocker to reverse it, means, part on the rocker and part on the dog, for determining which part of the rocker the dog shall engage, means for actuating said dog, a traveling cam, and means operated by said

cam for operating said rocker when the same is out of engagement with the dog.

57. In a calculating machine the combination of a totalizer, master means therefor, a rocker, means operated by the rocker for determining whether the master means shall cause addition or subtraction, a dog having hooks adapted to engage different portions of said rocker to reverse it, means, part on the rocker and part on the dog, for determining which part of the rocker the dog shall engage, means for actuating said dog, and a manually operated cam adapted to operate said rocker when the same is out of engagement with the dog.

58. In a calculating machine the combination of a totalizer, master means therefor, a rocker, means operated by the rocker for determining whether the master means shall cause addition or subtraction, a dog having hooks adapted to engage different portions of said rocker to reverse it, means, part on the rocker and part on the dog for determining which part of the rocker the dog shall engage, a manually operated lever for actuating said dog, a manually operated cam for operating said rocker when said rocker is disengaged by said dog, and means upon said lever for presenting said cam to and withdrawing it from said rocker.

59. In a calculating machine the combination of a totalizer, master means therefor, a rocker, means operated by the rocker for determining whether the master means shall cause addition or subtraction, a dog having hooks adapted to engage different portions of said rocker to reverse it, means, part on the rocker and part on the dog for determining which part of the rocker the dog shall engage, a manually operated lever for actuating said dog, a manually operated cam for operating said rocker when said rocker is disengaged by said dog, means upon said lever for presenting said cam to and withdrawing it from said rocker, and other means comprising a lever and a traveling cam for operating said rocker when the latter is free to move.

60. In a calculator, keys, a master wheel operable by said keys, a carriage, a jumping totalizer operable by said carriage, and a handle adapted to simultaneously render the keys non-operative upon the master wheel and the carriage non-operative upon the totalizer.

61. In a calculator, keys, a master wheel operable by said keys, a handle, connections operated by said handle and adapted to disconnect the keys from the master wheel, a carriage, a slidable totalizer and discon-nectable connections between said carriage and said totalizer, the last mentioned connections being adapted to be disconnected by said handle.

62. In a calculator, keys, a master wheel 65 operable by said keys, a handle, connections operated by said handle and adapted to disconnect the keys from the master wheel, a carriage, a slidable totalizer, a projection on said totalizer adapted to be engaged by said 70 carriage for causing the totalizer to travel, and means operated by said handle for holding said projection out of the path of the carriage.

63. In a calculator, a set of decimal 75 wheels, a master gear adapted to drive said decimal wheels, a jumper adapted to connect the master gear to said decimal wheels, a carriage adapted to advance the jumper, and a handle for rendering the carriage 80 non-operative upon the jumper.

64. In a calculator, a jumping totalizer, an element mounted on the totalizer for causing the same to travel, a traveling lug adapted to engage said element to cause the 85 forward travel of the totalizer and means for retaining said element out of the path of said lug.

65. In a calculator, a carriage, a slidable totalizer, a movable projection on said totalizer, a lug on said carriage adapted to engage said projection to advance said totalizer, a spring tending to return said totalizer, and manually operated means for holding said projection out of the path of 90 said lug.

66. In a calculator, a carriage, a slidable totalizer, a movable projection on said totalizer, a lug on said carriage adapted to engage said projection to advance said totalizer, a spring tending to return said totalizer, a stationary cam adapted to release said projection from said lug and manually operated means for holding said projection 100 out of the line of action of said lug. 105

67. In a calculator, a totalizer, master means therefor, controlling means adapted to occupy three positions to cause said machine to add, subtract or not calculate, depending upon the position of the controlling means, a pair of levers operatively connected together and adapted to operate said controlling means, and a non calculating cam having two acting edges, one adapted to engage one of said levers and the other adapted to simultaneously engage the other of said levers to thereby positively hold the controlling means in non-calculating position. 110

68. In a calculator, a totalizer, master means therefor, controlling means adapted to occupy three positions to cause said machine to add, subtract or not calculate, depending upon the position of the controlling means, a pair of levers operatively connected together and adapted to operate said controlling means, and a non calculating cam having two acting edges, one adapted 120 to 125

to engage one of said levers and the other adapted to simultaneously engage the other of said levers, both of said cam edges being located on the same side of said levers.

5 69. In a calculator, a totalizer, master means therefor, a rocker, means operated by said rocker for causing the machine to add or subtract depending upon the position of said rocker, two levers connected to said 10 rocker for operating it, said levers being located in different paths, an adding cam traveling in one of said paths and adapted to operate one of said levers, and a subtracting cam traveling in the other of said 15 paths and adapted to operate the other of said levers.

70. In a calculator, a totalizer, master means therefor, a rocker, means operated by said rocker for causing the machine to add, subtract or not calculate depending upon the position of said rocker, two levers connected to said rocker for operating it, said levers being located in different paths, an adding cam traveling in one of said 25 paths and adapted to operate one of said levers, a subtracting cam traveling in the other of said paths and adapted to operate the other of said levers and a non-calculating cam adapted to engage both of said 30 levers simultaneously.

71. In a calculating machine, the combination of a totalizer adapted to add and subtract, automatic controlling means adapted to cause said totalizer to add or subtract, 35 manually operated controlling means adapted to cause said totalizer to add or subtract, said automatic and manual controlling means being alternative to thereby afford the operator a choice as to which of them shall operate, and manually operated means for reversing the direction of operation of the totalizer irrespective of the manner in which it would otherwise have operated, whereby the operator is afforded an 40 opportunity to correct errors.

72. In a calculating machine, the combination of a reversible totalizer, automatic controlling means adapted to cause said totalizer to add or subtract, manual controlling 50 means adapted to cause said totalizer to add or subtract, and a reversing handle for causing the totalizer to operate in the reverse direction from the one in which it would otherwise have operated.

55 73. In a calculating machine, the combination of a totalizer adapted to add and subtract, automatic controlling means for causing said totalizer to add or subtract, manually operated controlling means adapted to cause said totalizer to add or subtract, said 60 two controlling means being alternative whereby the operator may choose as to whether the control shall be automatic or manual, and a reversing handle common to

both of said controlling means whereby the 65 operator may correct an error regardless of whether the totalizer is temporarily under automatic or manual control.

74. In a calculating machine, the combination of a multidecimal reversible totalizer, automatic controlling means for determining whether the totalizer shall add or subtract, manually operated controlling means for determining whether the totalizer shall add or subtract, said two controlling 75 means being alternative whereby the operator has a choice as to whether the totalizer control shall be automatic or manual, a reversible actuating means for inserting a number into said totalizer digit by digit, 80 and a reversing handle for determining the direction in which the actuating means shall operate the totalizer.

75. In a calculating machine, the combination of a multidecimal reversible totalizer, a reversible master wheel adapted to insert a number in said totalizer digit by digit, 85 automatic controlling means for determining whether the totalizer shall add or subtract, manually operated controlling means for determining whether the totalizer shall add or subtract, said two controlling means being alternative, means for actuating the master wheel, and manually operated means for reversing the direction of rotation of the master wheel to thereby enable the operator to correct errors irrespective of whether the totalizer be temporarily under automatic or 90 manual control.

76. In a calculating machine, the combination of a multidecimal reversible totalizer, actuating means therefor, a carriage for causing the actuating means to insert the number into the totalizer digit by digit, 100 automatic controlling means for determining whether said totalizer shall add or subtract, said automatic controlling means being governed by the motion of the carriage, manually operated controlling means for determining whether said totalizer shall add 105 or subtract, said two controlling means being alternative to thereby afford the operator a choice as to which of them shall operate and manually operated means for reversing the direction of operation of the totalizer irrespective of the direction in 110 which it would have otherwise operated, whereby the operator is afforded an opportunity to correct errors.

77. In a calculating machine, the combination of a multidecimal reversible totalizer, actuating means therefor, a carriage for causing the actuating means to insert a number into the totalizer digit by digit, 120 automatic controlling means determining whether said totalizer shall add, subtract or not operate, said automatic controlling means being operated by said carriage, man- 125

ually operated controlling means determining whether said totalizer shall add or subtract, one only of said two controlling means being operative upon the totalizer at any one time, and manually operated corrective means for reversing the action of the actuating means upon the totalizer.

78. In a calculating machine, the combination of a reversible totalizer, actuating means therefor, keys for operating said actuating means, automatic controlling means for determining whether said totalizer shall add, subtract or not operate, manually operated controlling means for determining whether said totalizer shall add or subtract, one only of said two controlling means being operative at any one time, and manually operated corrective means for reversing the action of the actuating means upon the totalizer, whereby the operator is enabled to correct errors whether the totalizer be under automatic or manual control.

79. In a calculating machine, the combination of a reversible totalizer, actuating means therefor, keys for operating said actuating means, automatic controlling means controlling whether said actuating means shall actuate the totalizer or not and if so the direction in which the totalizer shall operate, manual controlling means controlling the direction in which the actuating means shall actuate the totalizer, one only of said two controlling means being operative at any one time, and a reversing lever operative upon both of said controlling means for the correction of errors.

80. In a calculating machine, the combination of a multidecimal reversible totalizer, a reversible master wheel, key mechanism actuating said master wheel, a carriage for causing the master wheel to insert a number into the totalizer digit by digit, both automatic and manual controlling means for determining whether the master wheel shall actuate the totalizer for addition or subtraction, said two controlling means being alternative, and means for disconnecting the key mechanism from the master wheel.

81. The combination with a typewriter having keys and a traveling carriage of a reversible totalizer, master mechanism operated by the typewriter keys for operating said totalizer, automatic controlling means determining whether said totalizer shall add or subtract, said automatic controlling means being operated by the typewriter carriage, manually operated controlling means determining whether said totalizer shall add or subtract, one only of said two controlling means being operative at any given time, and a reversing handle for reversing the direction of operation of the totalizer regardless of whether the totalizer is temporarily under automatic or manual control.

82. The combination with a typewriter having keys and a traveling carriage of a multidecimal reversible totalizer, master mechanism operated by the typewriter keys for operating said totalizer, the movement of the typewriter carriage causing the master mechanism to insert the number into the totalizer digit by digit, automatic controlling means determining whether said totalizer shall add or subtract, manually operated controlling means determining whether said totalizer shall add or subtract, said two controlling means being alternative, and a reversing handle for reversing the direction of operation of the totalizer regardless of whether the totalizer is temporarily under automatic or manual control.

83. In combination, a typewriter having keys and a traveling carriage, a multidecimal reversible totalizer, a reversible master wheel, the typewriter carriage causing relative travel between the totalizer and the master wheel whereby the number is inserted into the totalizer digit by digit, means operated by the typewriter keys for rotating said master wheel, automatic controlling means for determining the direction of rotation of the master wheel, said automatic controlling means being operated by the typewriter carriage, manually operated controlling means for determining the direction of rotation of the master wheel, one only of said two controlling means being operative at any one time, and a reversing handle for reversing the direction of rotation of the master wheel from the direction in which it otherwise would have rotated, regardless of whether the master wheel is temporarily under automatic or manual control.

84. In a calculating machine, the combination of a jumping totalizer, figure keys, actuating means operated by said figure keys for actuating the totalizer, a traveling member controlled by said keys, two controls for determining the direction of operation of the totalizer, one of said controls being manual and the other being automatic and operated by said traveling member and reversing means common to said two controls for reversing the direction of operation of the totalizer regardless of whether the totalizer is temporarily under the manual or the automatic control.

85. The combination with a typewriting mechanism; of computing mechanism operable concomitantly with said typewriting mechanism; a typewriter carriage; a bar moving therewith; cams having two tracks adjustably mounted on said bar; a follower whose position is positively determined by the level of said cam tracks; and a gear reversing device operated by said follower.

86. In a combined typewriting and computing machine, the combination with com-

puting wheels, of keys adapted to control said wheels, manual devices settable to determine how said keys shall control said wheels, automatic devices to determine how said keys shall control said wheels, and connections to put said combined machine at will under either automatic or manual control.

87. In a calculating machine, the combination of a totalizer, master mechanism therefor, two different controlling means each of which determines whether said master mechanism shall cause addition or subtraction, and means for rendering one of said controlling mechanisms non-operative when the other is operative.

88. The combination with a typewriter carriage and a single computing device capable of adding or subtracting, of means for intermittently and repeatedly causing said computing device to compute in different columns in a single traverse of the typewriter carriage, a series of cams connected to said carriage, a follower device to run upon said cams, a spring device to hold the follower upon the cams, and means controlled by said follower device for determining whether the computing device shall perform addition or subtraction.

89. The combination with a computing head including a master wheel, of mechanism for determining the rotation of said master wheel, manual means controlling said mechanism, automatic means controlling said mechanism, and means for determining which of said previously mentioned means shall control said mechanism.

90. In a combined typewriting and computing machine, the combination with computing devices, of an automatic controlling mechanism for governing the state of said computing devices, a manual controlling mechanism for governing the state of said computing devices, and means for rendering either of said controlling mechanisms effective at will.

91. In a combined typewriting and computing machine, the combination with numeral keys and a traveling carriage, of computing wheels, connections whereby said keys determine how far said wheels shall turn, controlling means for determining how said wheels shall turn under the influence of said keys, means connected to said carriage to determine by its travel how said controlling means shall be effective, manually operable devices for manipulating said controlling means, and connections for making either said carriage-operated control or said manual control effective at will.

92. In a combined typewriting and computing machine, the combination with numeral keys, a traveling carriage, and computing wheels, of cams traveling with said

carriage to determine how said keys shall control said wheels, manual means for determining how said keys shall control said wheels, and connections to make either said cams or said manual means effective at will.

93. In a combined typewriting and computing machine, the combination with numeral keys, computing wheels and a traveling carriage, of cams connected to said carriage for determining whether said keys shall cause said wheels to add or subtract, manual means for determining whether said keys shall cause said wheels to add or subtract, and connections for making either said cams or said manual means effective at will.

94. The combination with a typewriter carriage and computing mechanism capable of adding or subtracting, of a series of cams connected to said carriage, a follower device to run upon said cams, a spring device to hold the follower upon the cams, and means controlled by said follower device for determining whether the computing mechanism shall perform addition or subtraction.

95. The combination with a computing mechanism, of an automatic control for governing the state of said computing mechanism, and means for connecting said automatic control with or disconnecting it from said computing mechanism at will.

96. The combination with computing mechanism and a traveling carriage, of means controlled automatically by the carriage for controlling said computing mechanism, said means comprising two cam surfaces for a single column, two followers for engaging said surfaces, and spring means for pressing said followers bodily into engagement with said cam surfaces, whereby the effect of said cam surfaces and followers on the computing mechanism depends upon the relative positions of said cam surfaces.

97. The combination with computing mechanism and a traveling carriage, of means controlled automatically by the carriage for controlling said computing mechanism, said means comprising two cam surfaces for a single column, and two followers for engaging said surfaces and both acting to control the same computing mechanism.

98. The combination with computing mechanism and a traveling carriage, of means controlled automatically by the travel of the carriage for controlling said computing mechanism, said means comprising a cam device, a follower device, and a yielding support for said follower device, the computing mechanism being controlled by the motion of the follower device independent of its support and said support yielding to compensate for any excess depth of the cam device over that necessary to produce such independent motion.

99. The combination with means includ-

- ing a carriage for printing numbers, and means for adding and subtracting the printed numbers, of means controlled automatically by said carriage for causing said numbers to be added or subtracted depending on the position of said carriage, and manual means for causing said numbers to be added or subtracted at will, with provision for manually enabling and disabling said carriage controlled means. 10. The combination with means including a carriage for printing numbers, and means for adding and subtracting the printed numbers, of means controlled automatically by said carriage to cause the printed numbers to be added, subtracted or not computed depending on the position of said carriage, and manual means for causing said numbers to be added, subtracted or not computed at will, with provision for manually enabling and disabling said carriage controlled means. 101. The combination with means including a carriage for printing numbers, and means for adding and subtracting numbers so printed, of a subtraction cam set at a predetermined point along the line of carriage travel, means controlled by said cam for causing the number printed at such predetermined point to be subtracted, means for disabling said causing means without removing the cam, and manual means for causing a printed number to be subtracted. 102. In a calculating machine, the combination of computing members, a series of numeral keys for controlling said members, manual devices and also automatic devices to determine whether said keys shall control said members additively or subtractively, and means for at will causing the machine to operate either under automatic or under manual control. 103. In a calculating machine, the combination of computing members, two different controlling means each of which determines whether said computing members shall be caused to add or to subtract, and means for causing one of said controlling mechanisms to become non-operative when the other is operative. 104. In a calculating machine, the combination of a computing device capable of adding and subtracting, a travelling carriage, means for intermittently and repeatedly causing said computing device to compute in different columns in a single traverse of said carriage, a series of cams, a follower, a spring device to hold the follower upon the cams, and means controlled by said follower to determine whether the computing device shall perform addition or subtraction. 105. The combination with keys, and means controlled thereby for adding and subtracting numbers, said means including a part settable to one position for addition and to another position for subtraction, of a correction key, and means controlled thereby for reversing the setting of said part, that is to say, for setting it for subtraction in case it had been for addition, and for setting it for addition in case it had been for subtraction, said part returning automatically to its original setting upon the release of said key. 106. The combination with computing mechanism, means for setting said mechanism for addition and for subtraction, said means including a part shiftable to one position for addition and to another position for subtraction, of a correction key, and means operated by a depression of said key for reversing the original setting of said part regardless of what that original setting was, said part returning automatically to its original setting upon the restoration of said key to its normal position. 107. The combination with means including a carriage for printing numbers, and means for adding and subtracting numbers so printed, of a bar, cams mounted on said bar and adjustable along it to positions corresponding to columns in which numbers are printed, and means including a follower displaced by one of said cams and acting to cause the number printed in the column position corresponding to said cam to be subtracted. 108. The combination of printing mechanism including a traveling carriage, a set of digit keys, and means operated by said keys for printing numbers, of a cross computing device, a master wheel adapted to register numbers digit by digit in said computing device upon the operation of said digit keys, a bar, cams mounted on said bar and adjustable along it to different column positions, and means controlled by one of said cams for reversing said master wheel and thereby causing the number written in the column position corresponding to said cam to be subtracted in said computing device. 109. A calculating machine having reversing mechanism comprising shiftable members adapted to be set to cause the machine to either add or subtract and said machine having a device adapted to be moved from a normal to a special location, such motion of said device reversing the setting of said shiftable members irrespective of their previous setting. 110. A calculating machine having means settable to adapt the machine either to add or subtract, said settable means being temporarily shiftable to change from addition to subtraction or vice versa, and said machine having also means normally inactive but adapted when moved to operative position to temporarily shift said settable means and thereby reverse the operation of the ma-

chine irrespective of the kind of calculation it was set in condition to perform normally.

111. In a calculating machine adapted both to add and to subtract, settable means for changing from addition to subtraction and vice versa, a correcting handle, and a dog operated by said handle and adapted to

engage said settable means and reverse the same so as to make the machine subtract if it had been set to add and to make the machine ¹⁹ add if it had been set to subtract.

In witness whereof, I have hereunto subscribed my name.

JOHN C. WAHL
